UNITED STATES PATENT OFFICE.

JAMES M. McCLELLON, OF EVERETT, MASSACHUSETTS.

FIRE-BOX CONSTRUCTION.

1,105,526.

Specification of Letters Patent.

Patented July 28, 1914.

Application filed June 23, 1910. Serial No. 568,507.

To all whom it may concern:

Be it known that I, JAMES M. McCLELLON, a citizen of the United States, and a resident of Everett, in the county of Middlesex, State of Massachusetts, have invented an Improvement in Fire-Box Construction, of which the following description, in connection with the accompanying drawings, is a specification, like letters on the drawings, representing like parts.

This invention relates to fire-box construction and more particularly to fire-boxes of the locomotive type. The character of the invention may be best understood by reference to the following description of illustrative embodiments thereof shown in the accompanying drawings, wherein:

Figure 1 is a vertical section through a fire-box shown herein as embodying my invention; Fig. 2 is a vertical longitudinal section taken on line 2-2 of Fig. 1; Fig. 3 on an enlarged scale is a horizontal section taken on line 3-3 of Fig. 1; and Fig. 4 is a vertical section through a modified form of fire-box.

Referring to Fig. 1 in the drawings, the illustrative fire-box there shown comprises a crown formed of a plurality of sections 1 extending longitudinally or from front to rear of the fire-box, each of said sections preferably being of convexed channel form with the convexed sides of said sections facing the interior of the fire-box and the flanges of the sections extending upwardly away from the interior of the fire-box, said flanges being riveted or otherwise secured together. Preferably spaced above the crown sections described is a top herein formed of a sheet 3 arched substantially to conform to the contour of the usual barrel 5 and at its forward end (Fig. 2) may overlap the latter, as at 7, and be riveted or otherwise secured thereto. The top sheet may be strengthened by suitable ribs 9 spaced at intervals and extending transversely of said top sheet from side to side of the fire-box. Herein these ribs are T-shaped in section and are secured to the exterior of said sheet. To support the channel sections by this arched sheet there may be provided hangers herein in the form of stay plates 11 extending longitudinally of the fire-box, said plates being removably bolted or otherwise secured at their upper ends between opposed angle irons 13 which in turn are secured to said top sheet. The

stay plates 11 depend from said sheet and preferably have their lower ends interposed between the adjacent flanges of the crown sections and may be secured thereto by the rivets which connect said sections. To permit water and steam to circulate freely in the crown the stay plates may be provided with suitable apertures 15 (Fig. 2) spaced at intervals throughout the lengths of said plates. The front ends of the sections may be secured to a flue sheet 17. Herein the flue sheet is cut away or formed to conform to the contours of the crown sections and has a flange 19 (Fig. 2) extending away from the interior of the fire-box. The sections are of sufficient length to overlie said flange and may be riveted or otherwise secured thereto. Since the flange extends away from the interior of the fire-box the rivets securing the sections thereto will be effectually protected from the fire.

The side walls of the fire-box may be formed in any suitable manner. Herein the side walls each comprise outer and inner channeled or flanged sections 21 (Fig. 3), alternate sections having long flanges or webs 23 to which are riveted the intermediate sections. These webs are apertured at intervals as at 25 to permit free circulation through the walls. The upper and lower ends of the sections may be closed by suitable cups 27 riveted or otherwise secured thereto. To connect the side walls to the crown the sections preferably are flattened at their upper ends, and the top sheet 3 referred to may be extended down to overlap the flattened portions of said sections and may be riveted thereto. To provide communication from said side walls to the crown chamber formed between the crown sections and the top sheet, suitable nipples 29 may be expanded or otherwise secured in registering apertures in the overlapped portions of said top sheet and wall sections.

In Fig. 4 is shown a modification which is similar in many respects to that just described. In this modification the top sheet is riveted to the interiors of the outer sides of the wall sections, said sides being extended upward somewhat beyond the inner sides of the sections to overlap said sheet. Top sheet strengthening ribs 33 are provided, but instead of being secured to the upper side of said sheet preferably are secured to the under side thereof. In this modification

the hangers supporting the crown sections are in the form of rods 35 which may be flattened at their upper ends as at 37 and bolted or otherwise secured to the top sheet 5 ribs 33. The lower ends of said rods may be bifurcated to receive the adjointed flanges of the crown sections and may be bolted or otherwise secured thereto. If desired calking strips may be interposed between the 10 flanges of adjacent sections. In this modification closing cups are not provided for the tops of the side walls, but the latter may communicate with the crown chamber through their upper ends. To prevent any 15 possibility of spreading of the top sheet, stay rods such as 39 may be secured to the top sheet strengthening ribs adjacent the juncture of said sheet with the side walls.

The circulation in the crown chamber is 20 mainly in the direction of the length of said chamber and the crown sections in extending in the direction of the length of the chamber facilitate this circulation. The crown sections are without interruption or 25 obstacle in the directions of their lengths. At their front ends where they are secured to the flue sheet flange the sections are smooth and clean permitting a free, unhindered flow to or from the crown chamber 30 and barrel. The convexed sections provide for expansion and contraction without developing leakage strains. A section may readily be removed for replacement or repair, merely by the removal of the hanger 35 connections of the sections without disturbing other sections, the side walls, or any other parts of the fire-box. Or if desired a section may be taken out without disturbing the hangers, as by removing the bolts connecting such sections to the adjoining sections.

Having described selected embodiments 40 of my invention without limiting myself thereto what I claim as new and desire to 45 secure by Letters Patent is:

1. In a fire-box, the combination of crown sections extending in a direction from the front to the rear of the fire-box and each of convexed channel form with flanges projecting upward away from the interior of

the fire-box; a top spaced above said sections and forming a steam and water circulation chamber therebetween; and means connecting said flanges with said top to contribute to the support of said sections.

2. In a fire-box, the combination of crown sections extending in a direction from the front to the rear of the fire-box and each of convexed channel form with flanges projecting upward away from the interior of the fire-box; a top spaced above said sections and forming a steam and water circulation chamber therebetween; means connecting said flanges with said top to contribute to the support of said sections; and hollow walls secured to the outer sections and communicating with said chamber.

3. In a fire-box, the combination of crown sections extending in a direction from the front to the rear of the fire-box and each of convexed channel form with flanges projecting upward away from the interior of the fire-box; a top spaced above said sections and forming a steam and water circulation chamber therebetween; means connecting said flanges with said top to contribute to the support of said sections; and walls comprising series of hollow steam generating sections secured to some of said crown sections and communicating with said chamber.

4. In a fire-box, the combination of crown sections extending in a direction from the front to the rear of the fire-box and each of convexed channel form with flanges projecting upward away from the interior of the fire-box; a top spaced above said sections and forming a steam and water circulation chamber therebetween; means connecting said flanges with said top to contribute to the support of said sections; and a flue sheet formed to conform to the under contours of said sections.

In testimony whereof, I have signed my name to this specification, in the presence of two subscribing witnesses.

JAMES M. McCLELLON.
